CLAIM

We claim the ornamental design for radial foldout tool with multiple types of tools and bit storage, as shown and described.

DESCRIPTION

(63) Continuation-in-part of application No. 12/009,461, filed on Jan. 17, 2008.

FIG. 1 illustrates a first isometric view of the radial foldout tool in a closed position;

(51) **LOC (9) Cl.** **08-05**

FIG. 2 illustrates a second isometric view of the radial foldout tool in a closed position;

(52) **U.S. Cl.** **D8/105**

FIG. 3 illustrates a third isometric view of the radial foldout tool in a closed position;

(58) **Field of Classification Search** D8/99,

D8/58, 55, 356, 52, 107, 105; D19/65; 81/440,

30/162, 161, 155

See application file for complete search history.

FIG. 4 illustrates a fourth isometric view of the radial foldout tool in a closed position;

FIG. 5 illustrates a top isometric view of the radial foldout tool in a closed position;

FIG. 6 illustrates a first perspective view of the radial foldout tool in an open or partially open position;

FIG. 7 illustrates a second perspective view of the radial foldout tool in an open or partially open position;

FIG. 8 illustrates an isometric view of the radial foldout tool with a drive in an open position and coupled to a bit socket;

FIG. 9 illustrates a perspective view of a first bit holder of and detached from the radial foldout tool with an inserted hinge at a rotational end of the first bit holder; and,

FIG. 10 illustrates a perspective view of a second bit holder of and detached from the radial foldout tool with an inserted hinge at a rotational end of the second bit holder.

The features show in broken lines illustrate portions of the design that form no part of the claim.
